UNITED STATES PATENT OFFICE.

MADISON QUISENBERRY AND ARMEANOUS P. HAMBLEN, OF PRENTISS, OKLAHOMA.

SACK.

1,084,228.

Specification of Letters Patent. Patented Jan. 13, 1914.

Application filed May 28, 1913. Serial No. 770,552.

To all whom it may concern:

Be it known that we, MADISON QUISEN-
BERRY and ARMEANOUS P. HAMBLEN, citizens
of the United States, residing at Prentiss, in
5 the county of Beckham, State of Oklahoma,
have invented certain new and useful Im-
provements in Sacks; and we do hereby de-
clare the following to be a full, clear, and
exact description of the invention, such as
10 will enable others skilled in the art to which
it appertains to make and use the same.

This invention is directed to improve-
ments in sacks for use by cotton pickers, and
has for its object to produce an article of
15 this type so constructed that the same may
be conveniently and easily emptied.

A further object of the invention is to so
construct the device that after the same is
filled it may be conveniently weighed.

20 With these and other objects in view, this
invention resides in the novel features of
construction, formation, combination and ar-
rangement of parts to be hereinafter more
fully described, claimed and illustrated in
25 the accompanying drawing, in which:—

Figure 1 is a front view of the sack. Fig.
2 is a view showing the sack in the position
assumed when being emptied.

Referring to the drawing, the numeral 1
30 designates a sack, the same being formed
from any suitable fabric and has the side
edges of its back and front so stitched that
the sack is contracted at its middle, the pur-
pose of which will appear later. The lower
35 end of the sack is open at the bottom to form
a discharge mouth 2, said mouth being
adapted to be closed by the flap 3 which is a
continuation of the lower edge of the back.
The flap 3 has secured thereto a plurality of
40 buttons 4 which are engaged by the button
holes 5 formed in the transverse strip 6
which is secured to the front of the sack and
adjacent the lower edge thereof, said flap
serving to close the mouth 2.

45 It is of course obvious that other means
for closing the mouth may be substituted for
the buttons and button holes, if desired.

The upper edge of the back extends above
the upper edge of the front and has secured
thereto a neck band 7.

50 The upper end of the sack is provided with
a mouth 8 so that when the sack is being
emptied the cotton will be discharged from
the mouth 2 as well as the mouth 8.

Secured to the lower edge of the sack 1 is 55
a ring 9, which is for the purpose of sus-
pended the sack upon a scale when it is de-
sired to weigh the contents thereof.

From this construction it will be seen that
a sack has been provided which is narrower 60
at its center, thus permitting the cotton to be
emptied therefrom at both ends. To accom-
plish this it is only necessary that the picker
grasp the sack at its center, and as the sack
is larger at its ends than at its center, the 65
cotton will be readily discharged, it being
of course understood that the mouth 2 has
been opened upon releasing the flap 5 from
engagement with the buttons 4.

70 What is claimed is:—

A cotton picker sack comprising a front
and back, the side edges of which are so
stitched that the sack will be narrower at its
center, mouths for the upper and lower ends
of the sack, a flap carried by the lower end 75
of the back, buttons secured to the flap, a
strip stitched transversely of the front and
adjacent the lower edge thereof, button holes
formed in the strip for engaging said but-
tons, whereby the flap closes the mouth at
80 the lower end of the sack, said sack being
adapted to be grasped at its narrowed center
for discharging the contents from both
mouths simultaneously.

85 In testimony whereof, we affix our signa-
tures, in the presence of two witnesses.

MADISON QUISENBERRY.
ARMEANOUS P. HAMBLEN.
